UNITED STATES PATENT OFFICE.

ALBERTO I. WOODRING, OF WATERLOO, IOWA, ASSIGNOR, BY MESNE ASSIGNMENTS,
TO NATIONAL SAFETY DEVICES COMPANY, OF WATERLOO, IOWA.

SIGNALING APPARATUS.

Application filed March 16, 1922. Serial No. 544,232.

To all whom it may concern:

Be it known that I, ALBERTO I. WOODRING, a citizen of the United States of America, and a resident of Waterloo, Blackhawk 5 County, Iowa, have invented certain new and useful Improvements in Signaling Apparatus, of which the following is a specification.

My invention relates to improvements in 10 signaling apparatus, particularly to audible signaling devices, and the objects of my improvements are, first, to provide mechanism operable after an initial starting impulse imparted thereto to thenceforth automatically 15 actuate one or more signaling devices as desired; second, to combine in said mechanism different fluid-pressure motors to conjointly perform different functions pertaining to said automatic actions; third, to furnish 20 means for dissociating one from another of said signaling devices for separate actuations, and further, to otherwise improve the construction and operation of this 25 class of invention as will be hereinafter more fully described and pointed out in the claims.

These objects have been accomplished by the means which are hereinafter described and claimed, and which are illustrated in 30 the accompanying drawings, in which Fig. 1 is a diagrammatic elevation of my improved signaling apparatus, parts being shown in section or broken away; Fig. 2 is a central vertical section of an operating- 35 valve. Fig. 3 is a view, partly in side elevation and partly in vertical medial section, of the spring-barrel and dash-pot of the device. Fig. 4 is a side elevation of said parts including the contact-device, parts of the 40 dash-pot being shown in section. Fig. 5 is an elevation of the side of said spring-barrel and dash-pot opposite that of Fig. 4. Fig. 6 is a top plan of the parts shown in Figs. 3 to 5, with parts removed or broken away. 45 Fig. 7 is a central horizontal section of the starting-motor. Fig. 8 is a central horizontal section of the relay-motor.

My improved signaling apparatus may 50 be employed in any location for the operation of signals of any kind which include a movable operating element. It is especially designed for use on locomotives or motor-propelled cars or vehicles. As used thereon, it may be employed to cause audible signals,

such as a whistle or bell, and may at will, 55 be used to operate these singly or simultaneously.

The invention herein, combines various new features and functions with others which I have shown heretofore in my co- 60 pending applications for patents, Serial Numbers 481,986, 520,918 and 530,315.

As employed on railway locomotives or motor-cars, my invention is adapted to actuate a whistle-signal as an alarm for highway crossings or for other purposes, and to ring an alarm-bell simultaneously or when desired.

In the sounding of a whistle alarm at 70 highway crossings a special number of intermittent blasts are commonly prescribed by railroad regulation. This signal comprises two blasts each of two seconds duration separated and followed by silent intervals of one second each, and succeeded by 75 two blasts each of one second duration separated by a silent interval of one second.

Fluid pressure is preferably used in the different motors of said apparatus, which may be of any kind, but for vehicles of the 80 class mentioned, compressed air has been found to be most convenient and universally applicable.

The numerals 1 and 108 respectively designate a whistle and a bell as often used on 85 locomotives. The whistle has an operating lever 2 to open its valve. To actuate this whistle signal intermittently to produce a highway-crossing signal such as that heretofore described, I employ a rock-body 43 90 of annular shape adjustably secured upon a rock-shaft 48 concentrically. A disk 50 is fixedly mounted on the outer end of the shaft 48 on a squared portion thereof by means of a nut 49, this disk having a portion of its edge provided with teeth, and a bar 51, secured radially across the rock-body 43 by means of screws 52, has terminal teeth on its inner end which mesh adjustingly with any of the teeth on the disk 50. Said 100 rock-shaft 48 traverses centrally a housing 60 and a spring-barrel 58, being rotatably mounted in a bearing opening in an end partition of 60 between barrel 58 and the dash-pot 61. Said housing and dash-pot are integral with a body casting 9 which is pivotally mounted on a boss 10 fixed to some overhead support, depending therefrom, and the

body 9 may be held in a horizontally adjusted position by means of a set-screw 11. A spiral spring 59 is mounted within the spring-barrel 60 with its outer end secured 5 thereto and its inner end secured to said rock-shaft. Referring to Fig. 5, the numeral 54 denotes a bar positioned longitudinally and horizontally along one side of said housing, has a longitudinal slot 55 and is 10 secured to the housing for longitudinal adjustment by means of screws 56 fastened through said slot. One end of said bar 54 has terminal teeth 57 which mesh with any of the teeth 53 on the spring-barrel 58 15 which is seated in a hollow of the housing 60. The screws may be slightly loosened that the bar 54 may be slid back to unmesh its teeth from the teeth 53 before returning it to mesh with other teeth, thus varying 20 the tension of the spring 59.

That part of the rock-shaft 48 which extends into the dash-pot 61 has a crank 63 on whose pin is pivotally mounted one end of the connecting-rod 64 whose other end is pivotally connected to a cross-pintle 65 in a cupped opening of the piston 66 which fits said dash-pot. The interior of the dash-pot below said piston is filled with a quantity of oil 62. The piston has a vertical opening 30 in which is seated a ball check-valve 67. Referring to Fig. 4, the numeral 69 denotes a port in the wall of the dash-pot opening thereinto opposite the rock-shaft and leading outwardly into the upper end of a passage 68 which leads downwardly into communication with the horizontal passage 71 in the base of the dash-pot, and the inner end of this passage 71 has communication with the lower part of the dash-pot by means 35 of the port 70. A threaded adjusting screw 72 is seated in the passage 71, traversing also a stuffing-box 73 and this screw has a hand-wheel for turning it to cause it to more or less limit the discharge opening at the 40 lower end of the passage 68.

A portion of the circumferential periphery of the rock-body 43 is removed to provide a number of projections 44, 45, 46 and 47, the projections 44 and 45 being of a determined length, these being separated from each other and the teeth 45 and 46 being separated by intervals of a determined length. The teeth 46 and 47 are each of determined length and are separated by an interval of 55 a determined length of that preceding.

The numeral 74 denotes a starting-motor operated by compressed air derived from a supply in a reservoir 93. As shown in Fig. 7, this motor has a cylinder containing a reciprocating piston 75 with a rod 77 projecting outwardly therefrom. A helical spring 78 within said cylinder is mounted around said rod engaged between said piston and one of the cylinder heads. One end of a connecting-rod 85 is pivotally mounted on

a pintle 84 extending from the outer extremity of the rod 77, the other end of the rod 85 being adjustably connected to the rock-body 43 by means of a pintle-bolt 86 traversing a short longitudinal slot 85' in said rod. 70 This slot permits adjustment of the length of thrust of the rod 85 in varying the rocking movements of said rock-body to vary the speed thereof. The motor 74 contains a longitudinal passage 81, one end of which communicates by means of the port 79 with the interior of the cylinder, and its other end communicates by way of a port 82 with an angle-coupling 83 on the upper end of a vertical pipe 87 whose lower end communicates 75 with the chamber 88 containing a check-valve. An adjusting screw 80 is seated in the end of a cylinder 74 to vary the area of the port 79. A screw-plug 76 is fitted in the threaded opening in this end of the cylinder, and may be removed to permit the seating in said opening of a conduit leading to a registering device, not shown. 80

The projections 44 to 47 inclusive, when the motor 74 is actuated to rock the rock-body 43 in one direction tensioning the spiral spring 59, on the cessation of action of the motor and the consequent reversed rocking of the rock-body successively intermittently engage a contact-device and thrust it 90 outwardly. This contact-device comprises a pair of arms 39 pivoted on opposite sides of a swinging arm 37 on a pintle 40, the other ends having a roller 42 rotatably mounted between them in the path of rocking movements of said projections. Step-shoulders 38 on the lower end of the arm 37 are engaged by the arms 39 when the projections move downwardly so that said projections thrust the arms 39 and arm 37 swingingly 95 outwardly, although said arms 39 yield upwardly without swinging the arm 37 when the projections move upwardly. The arm 37 at its upper end has an angularly directed part mounted to rock in a bearing 36 100 forming part of a bracket-arm 41 fixedly mounted on said housing 60. The other end of this angular part is widened at 35 and has a vertical arm 34. 105

The numeral 8 denotes another motor cylinder fixed on or made integral with said housing and dash-pot, horizontal, and positioned above said housing. This cylinder, shown in section in said Fig. 8, contains in an end chamber 14 a reciprocating piston 12 110 fixed on a rod 4. The outwardly projecting end of said rod is squared and a squared sleeve 5 is mounted thereon slidingly. The rod has a number of bolt-holes 6 to receive adjustably a pivot-bolt 7 on one end of which 115 one end of a connecting-rod 3 is pivoted. The other end of said rod 3 is pivotally connected to the upper extremity of the whistle-operating lever 2. 120

The cylinder 8 is divided by means of 125

partitions into three chambers 14, 24 and 28. A cupped spring-housing 18 is exteriorly threaded and seated adjustably in a threaded opening in the partition 19 and 5 contains a short helical spring 20 which bears against the solid valve 23 to thrust it yieldingly against an orificed seat in the other partition 22, said valve having a boss 27 extending into the chamber 28, the boss 10 having a hemispherical end. The adjacent cylinder-head is orificed to seat the reciprocatory rod 29 whose inner end is hemispherically concaved to fit the rounded end of the boss 27 in alinement therewith, and the rod 15 29 has a longitudinal central bore 30 whose outer end is angularly directed to open outwardly of the cylinder when the rod is in one position. On the threaded outer extremity of said rod 29 is adjustably mounted a 20 socket-nut 32 secured thereto by means of a set-screw 33. The convex outer end of the nut 32 contacts the adjacent vertical face of the arm 34. The numeral 21 denotes a by-pass in the cylinder 8 connecting the two 25 outermost chambers 14 and 28. The numeral 25 denotes a coupling-member, one end of which is in communication with the chamber 24, the bore of said member being adjustably varied by means of an adjusting-screw 26. The outer end of the member 25 is in communication with an angle-coupling 97, a riser 96, and a horizontal pipe 95, the latter coupled at 94 to the vertical supply pipe 92 which leads to the air reservoir 93. 30 The chamber 14 of the cylinder 8 contains a helical spring 13 around the rod 4 and engaged between said piston 12 and the left-hand head of the cylinder. An adjusting-nut 31 is mounted on the inward end of the 35 rod 29 to variably limit the outward movement thereof.

Said cylinder has a port 15 in communication with an elongated valve-chamber 16 containing a ball check-valve 17, and said chamber has a communication with an angle-coupling 98, a riser 99, a horizontal pipe 100, and a riser 101, the lower end of the latter communicating by means of a T-coupling 102, with a conduit 105 which leads 40 to the compressed air motor 106 which, in a well known way, may actuate a plunger to thrust upwardly on an eccentrically mounted stem 107 fixed on a crank-pin of said bell 108. A valve-chamber 103 is in communication between the coupling 102 and a coupling 109 connecting sections of the supply-pipe 92, said chamber containing an orificed rock-valve manually actuatable by 45 means of a handwheel 104.

60 A horizontal pipe 89 connects the check-valve chamber 88 with a T-coupling 91 of the supply pipe 92 above the valve-chamber 103. A valve-chamber 90 connects and places in occasional communication the 5 parts of the pipe 89. As shown in Fig. 2,

the lower part of this chamber 90 has a compartment 123 in which is mounted the vertically movable valve 122. The diminished lower part of the valve is surrounded by a short helical spring 126 which tends to 70 yieldingly thrust the valve upwardly against its seat closing the port 121 which leads into a chamber 118. On said valve is fixed an upright channeled part 120 forming a guide within said port, and on said member 120 is fixed an upright stem 119 with hemispherical upper extremity. In the removable upper section 114 is a central opening in which is slidably mounted a reciprocable stem 115 having a longitudinal 80 central bore 116 whose upper end is directed outwardly to communicate with the atmosphere when the stem is in its uppermost position. The lower end of the stem 115 is of larger diameter than the stem 119 and 85 has a hemispherical socket 117 to receive and fit the hemispherical upper end of said stem 119. The lower section 90 has a port 125 effecting communication between the lower chamber 123 and the left-hand section of said pipe 89 leading to the supply pipe 92. Said section 90 also has in its opposite side a port 124 effecting communication between the chamber 118 and the right-hand section of the pipe 89. Spaced down-curving lugs 113 project upwardly from the section 114 and are connected by a pintle 112. The numeral 110 denotes an operating handle having a flattened part provided with a notch 111 in which the pintle 112 is seated, and the lower edge of the flattened part is curved downwardly to normally be positioned above and rest upon the top of the stem 115. The handle 110 is positioned in the apparatus conveniently for manual 90 manipulation by an engineer, but I have also provided another operating valve 129 below which is of the same construction as that just described, but is provided with an operating pivoted pedal 130 instead of said 95 handle 110. The arm on which this pedal is mounted curves over and contacts with the stem 115 in the same way. The respective ports 125 and 124 of the lower chamber 129 are likewise in communication 100 with sections of the horizontal pipe 128, the left-hand section of which communicates by means of a T-coupling 127, with the said supply-pipe 92, while the other section communicates with the sectional riser 131 which 105 leads into the bottom of the check-valve chamber 88.

I have also provided means for use in automatically operating the apparatus by engagements of an operating element with 110 contact-blocks 144 positioned shortly in advance of the highway crossing as the vehicle is in translatory passage past them. The numeral 137 denotes a valve-chamber whose 115 interior is divided by means of a partition 130

140 into two compartments, said partition having a valve-seat to seat the coned head valve 139 which has a stem depending through an opening in the bottom of the 5 chamber. Said stem has an angular passage 141 adapted, when the valve is seated, to effect communication between the right hand compartment and also the riser 135, and the atmosphere below said chamber.

10 The upper end of the riser 135 leads into the bottom of a chamber 134 containing a check-valve, and said chamber communicates by way of a short pipe 133 and a coupling 132 with the riser 131 below the other check- 15 valve chamber 88. The left-hand compartment of the chamber 137 has communication by way of a horizontal pipe 136 and an angle-coupling with the lower end of the supply-pipe 92. The numeral 142 denotes 20 a vertical reciprocable stem on whose lower end a roller 143 is rotatably mounted to ride upon and along the track abutment 144. The stem 142 is seated slidably in an opening in a bracket 148 fixedly mounted on the 25 vehicle, and passes through the hollow housing 147 in line with the valve-stem above it. The stem 142 has an annular flange 145 within said housing, and a helical spring 146 is mounted around said stem engaged 30 between said flange and the top of the housing.

Operation: The valve in the valve-chamber 104 may be kept closed usually, when it is to be ordinarily used only manually in 35 the operation of the bell 108 in the usual way, as the bell is actuated by the motor 106 when the said valve is opened by means of the hand-wheel 104. If it is desired to have the bell operated simultaneously with 40 the operation of the whistle 1, the valve is left closed. When the engineer manually or pedally actuates the handle 110 or the pedal 130 of the like operating-valves in the chambers 90 or 129, the stem 115 is forced 45 downwardly against the stem 119 pushing open the valve 122, whereby a communication is established between the chambers 123 and 118, so compressed air may pass from the pipe 92 through said operating-valve to 50 the pipe 89 and check-valve 88 by way of said ports 125 and 124. The check-valve is thus lifted, air passing through the riser 87 to the starting-motor 74, pushing the piston 75 to the right, compressing the spring 78, 55 the connecting-rod 85 then rocking the rock-body 43 upwardly while placing the spiral spring 59 under tension, the projections 44 to 47 idly moving the arms 39. The engineer then releases the operating valve, the 60 spring 126 reacts to close the valve 122, while the compressed air in the chamber 118 pushes up the stem 115 to the elevated position shown, separating the lower socketed end of the stem 115 from the upper end of 65 the stem 119, permitting air to exhaust from

the chamber 118 through the bore or passage 116 to the atmosphere, as also from the motor 74 and the passages leading to said chamber 118.

The springs 78 and 59 now are released 70 and react, the latter returning the rock-body 43 to its first position, the projections 44 to 47 inclusive engaging and successively thrusting outwardly the roller 42 and the arms 39 with the arm 37, as the arms 39 are 75 stopped by the shoulders 38. The arm 34 is thus rocked to push in the hollow stem 29, closing its exhaust-port, and the stem 29 in turn engages the boss 27 to push open the valve-head 23. The compressed air in the 80 chamber 24 now passes into the chamber 28, through the by-pass 21 to the chamber 14, thrusting to the left the piston 12, compressing the helical spring 13, and by means of the piston-rod 4 shifting the connecting-rod 85 3 and the whistle-operating lever 2 to the left to sound the whistle at each actuation 85 of the contact-device by the projections on the rock-body, the durations of the blasts and their intervals being such as already 90 described for a highway-crossing signal. It will be seen that the relay-motor 8 thus effectively acts in supplying the considerable power necessary to be employed in operating the whistle-lever, and removes this burden 95 from the operator. At each cessation of action of the contact-device, the arm 34 returns to the right because of the air-push on the annulus 31, separating the stem 29 from the boss 27, and as the exhaust-port in 100 the stem 29 now opens to the atmosphere, air is exhausted from the chamber 12 by way of the by-pass 21 and the chamber 28. The spring 13 reacts to return the piston 12 to its initial position. At each end of the rocking 105 movements of the rock-body 43, the piston 66 in the dash-pot 61 in moving compresses the oil contents 62 to cushion the action effectively in relieving the spring 59 from excessive strain and preventing jarring of the 110 moving parts, ensuring smooth operation. A portion of the fluid at each compression moves through the bottom port 70, thence upwardly through the passage 68 to the upper port 69, and through this port into 115 the dash-pot upon said piston, and as the piston is lifted, this fluid moves down through the piston-port 67.

When the abutments 144 are provided along the line, for actuation of the valve 120 139, each such actuation permits passage of the compressed air into the riser 135, whence it passes the check-valves in the chambers 134 and 88, and by way of the riser 87 enters the starting-motor 74, operating the whistle-signal in the manner above described. 125

An important feature of my invention is the provision of means for operating the bell signal 108 at each actuation of the whistle-signal. This is effected as follows. 130

The valve in the chamber 103 being closed, and the operating-valve 90 being actuated by the engineer, the apparatus functions as above described in producing the whistle signal. When compressed air is delivered into the relay-motor chamber 12 it pushes back the ball check-valve 17 in said chamber 16, permitting the fluid to pass by way of the communicating pipes 99, 100 and 101 to the pipe 105 and the bell-motor 106 thus causing the latter to ring the bell 108. The bell is operated during the actuations of the whistle by its own momentum, and will continue ringing for some time after the air is exhausted from the chamber 14, because of its own momentum.

It is to be understood that considerable modifications may be made in my said invention, without departing from the principles thereof or from the scope of its protection.

Having described my invention, what I claim as new and desire to secure by Letters Patent, is:

1. In a signaling apparatus, a signaling device having a movable operating element, a resiliently-controlled rock-body having projections, a contact-device connected operatively to said operating element and actuated by the projections on said rock-body with step-by-step movements to operate the signaling device, a motor actuated by and having a communication with a source of fluid under pressure, a valve-chamber in said communication, a resiliently-controlled valve in said chamber, a valve-operating element in said chamber projecting therefrom and having a release-port for exhausting the fluid from said motor only when the valve is closed after having been opened, and operating connections between said motor and said rock-body.

2. In a signaling apparatus, a signaling device having a movable operating element, a resiliently-controlled rock-body having projections, a contact-device connected operatively to said operating element and actuated by the projections on said rock-body with step-by-step movements to operate the signaling device, a motor actuated by and having a communication with a source of fluid under pressure, a valve-chamber in said communication, a resiliently-controlled valve in said chamber, a valve-operating element in said chamber projecting therefrom and having a release-port for exhausting the fluid from said motor only when the valve is closed after having been opened, operating connections between said motor and said rock-body, and a relay-motor actuated by said fluid and also in communication with said source of fluid pressure by way of said valve-chamber, said relay-motor being operatively positioned between and connected to elements of said movable operating element

and said contact-device to thrust the former at each actuation of the latter by said rock-body.

3. In a signaling apparatus having a movable operating element, a resiliently-controlled rock-body having spaced projections, a contact-device connected operatively to said operating element and actuated by the projections on said rock-body with step-by-step movements to operate the signaling device, a motor actuated by fluid under pressure, connected to and adapted to rock said rock-body in one direction, a valve-chamber containing a check-valve in communication with said motor, a valve-chamber containing an operating-valve in communication with said check-valve chamber and with a source of fluid under pressure, and said valve-chamber containing means for exhausting said fluid therefrom after an actuation and release of its operating-valve.

4. In a signaling apparatus having a movable operating element, a resiliently-controlled rock-body having spaced projections, a contact-device connected operatively to said operating element and actuated by the projections on said rock-body with step-by-step movements to operate the signaling device, a motor actuated by fluid under pressure, connected to and adapted to rock said rock-body in one direction, a valve-chamber containing a check-valve in communication with said motor, a valve-chamber containing and operating-valve in communication with said check-valve chamber and with a source of fluid under pressure, said valve-chamber containing means for exhausting said fluid therefrom after an actuation and release of its operating-valve, a by-pass conduit also in communication with said check-valve and with said source of fluid supply, a second valve-chamber in said communication containing an operating-valve, the last-mentioned chamber containing means for exhausting said fluid therefrom after an actuation and release of its operating-valve, and independent means for actuating said operating-valves.

5. In a signaling apparatus, a source of fluid supply under pressure, a whistle-signal having a movable operating element, a bell-signal, a motor actuated by fluid pressure operatively connected to said bell-signal, a resiliently-controlled movable body having projections, a contact-device actuated by the projections on said movable body with step-by-step movements, a starting-motor actuated by fluid pressure operatively connected to said movable body, a relay-motor having an element operatively connected to said whistle-operating element, said relay-motor being in communication with said source of fluid supply, and containing resiliently-controlled valvular means actuated by said contact-device for

making and breaking communication of the motor with said fluid supply and including means for exhausting such fluid therefrom after such making and breaking actu- 5 ations, other means of communication be- tween said relay-motor and said bell-motor including a valve-chamber containing a check-valve, means of communication be- 10 tween said starting-motor, said source of fluid supply and the said communication between the relay-motor and the bell-motor and containing a valve-chamber, an operating-valve in said chamber, and means in 15 said chamber for exhausting said fluid from said starting motor after operation and re- lease of said operating-valve.

6. In a signaling apparatus, a source of fluid supply under pressure, a whistle-sig- 20 nal having a movable operating element, a bell-signal, a motor actuated by fluid pressure operatively connected to said bell- 25 signal, a resiliently-controlled movable body having projections, a contact-device actuated by the projections on said movable body with step-by-step movements, a start- 30 ing-motor actuated by fluid pressure operatively connected to said movable body, a relay-motor having an element operatively connected to said whistle operating-element, 35 said relay-motor being in communication with said source of fluid supply, and containing resiliently-controlled valvular means actuated by said contact-device for making and breaking communication of the 40 motor with said fluid supply and including means for exhausting such fluid therefrom after such making and breaking actuations, other means of communication between said relay-motor and said bell-motor including a valve-chamber containing a check-valve, means of communication between said start-

ing-motor, said source of fluid supply and the said communication between the relay- 45 motor and the bell-motor and containing a valve-chamber, an operating-valve in said chamber, and means in said chamber for ex- hausting said fluid from said starting-motor after operation and release of said operat- 50 ing-valve, and valvular means for manually controlling the communication between said source of fluid-supply and said bell-motor.

7. In a signaling apparatus, a source of fluid supply under pressure, a whistle-sig- 55 nal, a bell-signal, mechanism for inter- mittently actuating said whistle-signal in- cluding a starting-motor and a power- 60 relay motor in communication respectively with said source of fluid supply, an actu- ating motor for said bell-signal operated by fluid-pressure, an operating-valve in 65 communication with said source of fluid supply, and said starting-motor, and con- trollable means of communication between 70 said bell-motor and said relay-motor.

8. In combination, a bell signaling de- 65 vice, a fluid-operated motor operatively connected to said bell signaling device, a valve- 70 chamber in communication between said bell motor and a supply of fluid under pressure, resiliently controlled valvular 75 means in said valve-chamber for controlling said communication, a resiliently controlled operating element having a cam thereon, and valve-tripping means associated with said valvular means and operative to actu- 80 ate the latter by engagement with said cam only when the latter has been shifted in one direction and is reactively returning to its first position.

Signed at Waterloo, Iowa, this 13th day 80 of March, 1922.

ALBERTO I. WOODRING.
